UNITED STATES PATENT OFFICE.

ANDREW NILSON, OF CHICAGO, ILLINOIS, ASSIGNOR TO EUREKA SMOKELESS FURNACE CO., OF CHICAGO, ILLINOIS.

FURNACE.

Application filed June 17, 1920. Serial No. 389,689.

To all whom it may concern:

Be it known that I, ANDREW NILSON, a citizen of the United States, residing at Chicago, in the county of Cook and State of Illinois, have invented a certain new and useful improvement in Furnaces, of which the following is a full, clear, concise, and exact description, reference being had to the accompanying drawings, forming a part of this specification.

This invention relates to furnaces, and more particularly to a furnace provided with a baffle wall in the fire box to provide a combustion chamber to the rear thereof.

This invention has for its purpose to provide means for the shaking of the grate sections rearwardly of the baffle wall separate from the means for shaking the grate forwardly thereof.

This invention also has for its purpose the provision of means to prevent cold air from the ash pit from following a path along the water leg and lower tubes of the boiler, without mixing with the hot gases in the combustion chamber, the rear grate section being provided with perforations only over half its area for this purpose.

Other objects and advantages of the invention will become apparent as the description of the accompanying drawings proceeds, in which:—

Fig. 1 is a longitudinal vertical sectional view of the improved furnace, showing the fire box portion thereof, the boiler being partly broken away;

Fig. 2 is a fragmentary sectional view on line 2—2 of Fig. 1, showing the rear portion of the grate and associated parts.

Referring now more in detail to the accompanying drawings the improved furnace comprises a fire box 3 having a roof 4 and a rear wall 5, the lower portion of which comprises the water leg 6. In the fire box 3 is provided a baffle wall 7 that rests on a member 8 through which water can circulate. The baffle wall 7 is provided with a channel 9 opening toward the front of the furnace in the upper portion thereof and extending downwardly and rearwardly into the combustion chamber 10 that is provided rearwardly of the baffle wall 7. Separating the fire box 3 and the ash pit 11 is the grate 12 which comprises a plurality of pivotally mounted grate sections 13 and 14.

The grate sections 13 are secured together by the bar 15 to which they are pivotally connected and which has pivotally connected thereto the shaker bar 16, which is provided with a suitable socket member 17 for receiving an operating handle, the socket 17 being suitably pivoted to ears on the furnace front 18. The grate sections 14 are pivoted to the connecting bar 19 that has pivotally connected thereto the shaker bar 20, which is suitably pivoted to the socket member 21 pivoted between the ears 22 on the furnace front 18. The grate sections 14 are below that portion of the fire box rearwardly of the baffle wall 7, or in other words, these grate sections 14 separate the combustion chamber from the ash pit. The grate section 14, adjacent the grate sections 13, is a duplicate of these grate sections 13 and comprises a central web 23 and laterally projecting teeth 24 providing openings 25 therebetween. The grate section 14, adjacent the rear wall of the fire box, is provided on one side thereof with the teeth 24, while the other side 26 thereof is made in one solid piece extending substantially over to the shelf 27 provided at the rear of the fire box, only enough space being left to permit of the shaking of this grate section.

Ordinarily if the grate sections 14 at the rear of the fire box were made as are the remaining grate sections, a stream of cold air from the ash pit would flow through the perforations in the rear half of this grate section and would follow the water leg 6 along the wall thereof as indicated by the arrows in Fig. 1, and then along the lowermost flues without mingling with the heated gases in the combustion chamber 10, thus cooling the water leg 6 and adjacent portions of the boiler and resulting in the loss of the oxygen in the air, thus passing along the water leg, for carrying out the processes of combustion in the chamber 10. By providing the rear grate sections 14 with an imperforate portion in the rear thereof, the cold air from the ash pit is forced through the perforations between the teeth on the remaining grate sections, and as it is then passing through the grate at a considerable distance from the water leg 6 this air will mingle with the hot gases in the combustion chamber 10 and will become thoroughly heated and mixed therewith and will aid in

the combustion of the gases contained therein and instead of cooling the boiler will aid in heating it.

It will be noted that the grate sections 14 are entirely independent of the grate sections 13, the grate sections 13 all being connected together and operated by a single handle to shake the same, and the grate sections 14 being connected together and being 10 operated by a different handle. In the use of a furnace with a baffle wall, such as that shown, the coal is piled up against the baffle wall and is permitted to fall rearwardly of the baffle wall in such position as it would 15 assume due to its own weight. When the coal is in this position it is often necessary and desirable to clean the rear portions of the grate without disturbing the coal in the forward portion of the fire box, and in order 20 to do this the rear grate sections must be arranged so as to be operated independently of the forward grate sections. This is accomplished by mounting the two rear grate sections 14 so as to be shaken independently 25 of the grate sections 13. It will be seen from the above that a means has been provided for deflecting the cold air entering from the ash pit away from the water leg and thus causing the same to be properly 30 mixed with the heated gases in the combustion chamber, and that there has also been provided a means for properly cleaning the grates rearwardly of the baffle wall by providing a separate means for shaking the 35 same.

Having thus described my invention I desire to have it understood that I do not intend to limit myself to the exact details shown and described except as defined in the 40 following claims:—

1. In a furnace a grate comprising a plurality of pivoted grate sections, said grate having openings therein formed between

portions of said grate sections, the rear grate section being provided with openings only 45 at one side of the center line thereof.

2. In a furnace a grate comprising a plurality of pivoted grate sections, said grate having openings therein formed between portions of said grate sections, the rear grate 50 section being provided with openings only forwardly of the center line thereof.

3. In a furnace a fire box provided with a water leg at the rear wall thereof, an ash pit and a grate extending over the entire 55 area of said fire box and separating said fire box and ash pit, and provided with openings therein to admit air from said ash pit, said grate being imperforate adjacent said water leg.

4. In a furnace an ash pit, a fire box, a grate separating said fire box and said ash pit and having openings for permitting air to enter said fire box from said ash pit, a water leg at the rear of said ash pit, and a 60 baffle wall providing a combustion chamber rearwardly thereof, said grate being provided with means to deflect the air from said ash pit away from said water leg and toward the center of said combustion chamber. 70

5. In a furnace an ash pit, a fire box, a grate separating said fire box and said ash pit and having openings for permitting air to enter said fire box from said ash pit, a water leg at the rear of said ash pit, and a 75 baffle wall providing a combustion chamber rearwardly thereof, said grate being provided with means to deflect the air from said ash pit away from said water leg and toward the center of said combustion chamber, and means to shake the portion thereof rearwardly of said baffle wall independently of the portion forwardly of said wall. 80

In witness whereof, I hereunto subscribe my name this 14th day of June, A. D., 1920. 85
ANDREW NILSON.
